UNITED STATES PATENT OFFICE.

ROBERT S. BOHANNAN, OF ENSLEY, ALABAMA, ASSIGNOR TO NATIONAL STEEL PRODUCTS COMPANY, A CORPORATION.

GUARD-RAIL STRUCTURE.

1,268,087.

Specification of Letters Patent.

Patented June 4, 1918.

Application filed August 25, 1917. Serial No. 188,153.

To all whom it may concern:

Be it known that I, ROBERT S. BOHANNAN, a citizen of the United States of America, residing at Ensley, in the county of Jefferson and State of Alabama, have invented certain new and useful Improvements in Guard-Rail Structures, of which the following is a specification.

This invention relates to guard rails for railway tracks, and its objects are to provide in a light, strong and compact body a combination guard rail, foot guard and guard rail clamp, in which all wear from the wheel flanges is received by a thin replaceable wear strip inset into the guard rail and inclined away from the rail.

My improved guard rail clamp or fastening means contemplates the adjustment of the guard rail to the traffic rail by means of a key to allow for various flange way distances and I provide this key with lugs which engage the top and bottom of the rail base to hold the key in position when spiked to the tie. To provide the maximum facility of adjustment, the key is given a wedge shape and is notched to receive the fastening spike.

To produce a guard rail that is exceedingly light but amply strong for the service required of it, the guard rail proper terminates at the level of the web forming the foot guard, being supported below by arches which span from cross tie to cross tie and have for their bases rail base plates which extend under the traffic rail. The center plate has lugs which overhang the key and a slot disposed to permit the key spike to be driven in at any point where the key comes to rest.

My invention also comprises the novel details of construction of the guard rail which are more particularly pointed out in the appended claims, reference being had to the accompanying drawings to illustrate the preferred embodiment only of the same.

In the drawings:

Figure 1 shows my improved guard rail in plan view.

Fig. 2 shows the rail in side elevation.

Fig. 3 is a sectional view taken on the line 3-3 of Fig. 1.

Fig. 4 is a view taken on the line 4-4 of Fig. 1.

Fig. 5 is a detail perspective view of the key seat on the rail plate extension of the guard rail.

Fig. 6 is a perspective view of the wedge key.

Similar reference numerals refer to similar parts throughout the drawings.

The guard rail 1 is curved in plan view 60 and is supported at its center by a narrow integral web 2 which joins and is braced to a rail base plate 3 by the web 4. The ends 5 of the guard rail incline downwardly and join to integral base plates 6. The guard 65 rail is thus in effect supported in elevated position by integral arches which span the cross ties. Integral with the guard rail is a horizontal web 7 which at its ends is widened and curved downwardly to join 70 the base plates 6, thus forming a foot guard. The guard rail proper terminates with the base of the web 7 above which it is inclined outwardly away from the rail 8, see Fig. 3, its inclination conforming to the shape 75 of the wheel flange 9. An interchangeable wear plate 10 of hard metal has its end edges beveled and is adapted to be inserted downwardly in a dove-tail seat 11 formed in the inner face of the guard rail proper 80 and extending practically from end to end thereof or at least throughout the intermediate portion of the flange way where the wear comes on the guard rail. This replaceable wear plate is held in place by rivets 85 12 having their heads countersunk on its wearing face and their bodies extending through the riveted to the guard rail proper.

The rail base plates 3 and 6 are spaced 90 by the arch supports for the guard rail on centers corresponding to the spacing of the cross ties 13, each plate projecting on one side of the guard rail sufficiently to permit spikes to be readily driven through the 95 notches 14 provided therefor to hold down the guard rail on the side away from the traffic rail 8. The base plates 6 extend under the base of the traffic rail and are provided with holes 15 to receive rail engaging 100 spikes. The center base plate 3 also extends under the base of the traffic rail and along its edge beyond such rail it is provided with a raised shoulder 16 set at an angle to the traffic rail and provided at 105 each end with lugs 17 and 18 under which the wedge key 19 is adapted to be driven. This key, as shown in Fig. 6, is provided near its center with a lug 20 adapted to overhang the base of the traffic rail and near 110

its wide end with a lug 21 adapted to underlie the base of the traffic rail. Opposite the lug 20, the key is provided with a spike notch 22 and as the key is driven in between the shoulder 16 and the traffic rail this spike notch 22 travels along over a slot 23 formed on the base plate 3 so that at any point where the key comes to rest a spike 24 may be driven through notch 22 and slot 23 into the tie to fasten the key in position.

The wedge key is driven in under the lugs 17 and 18 of the base plate 3 to the distance necessary to get the proper adjustment between the guard rail and the traffic rail and the spike 24 will hold the key fixed in this position. The width of the foot guard web 7 is preferably such as to stop short of a vertical plane through the adjacent edge of the traffic rail tread, thus providing ample clearance for dirt and trash to pass out between the web and the rail. The ends of the guard rail proper are curved outwardly to catch and guide the wheel flange through the flange way and are curved downwardly to avoid catching on any moving part of the train. By stopping the guard rail proper at the under level of the foot guard web 7 and supporting it by arches resting on the base plates 3 and 6, I eliminate all superfluous metal without sacrificing the necessary strength. The base plates, as shown in Fig. 3, may be provided with down turned spuds 25 which are driven into the tie and more firmly secure the guard rail in position.

It is only necessary to cause the web 3 or center of the base of the guard rail to abut against the base of the traffic rail, as by curving the guard rail supports away from the traffic rail, the ends are supported in such spaced position from the traffic rail as to greatly strengthen and brace the center of the guard rail against lateral thrust strains.

Having thus described my invention, what I claim as new and desire to secure by Letters Patent, is:

1. A guard rail having an integral base plate, means to clamp said plate to a traffic rail resting thereon, and a thin replaceable wear plate mounted in the face of the guard rail opposite the traffic rail head.

2. A guard rail having integral base plates adapted to support thereon a traffic rail, and a thin replaceable wear strip covering the surface of the guard rail most exposed to wear from the flanges of wheels moving on the traffic rail.

3. A guard rail having an integral foot guard, means to fasten the guard rail in position relatively to a traffic rail, and a thin replaceable wear strip inserted in the face of the guard rail above the foot guard.

4. A guard rail having an integral foot guard, means to fasten the guard rail in position relatively to a traffic rail, and a thin replaceable wear strip dove-tailed and

riveted into the face of the guard rail above the foot guard.

5. In a device of the character described, a plurality of spaced base plates adapted to extend under a traffic rail, arch shaped webs integral with said plates, vertical and horizontal webs integral with the arch webs and forming respectively a guard rail and a foot guard, the guard rail having its inner face inclined away from the traffic rail and curved with its convex face toward the traffic rail, and a replaceable wear plate covering the intermediate convex surface of the guard rail, substantially as described.

6. In a device of the character described, a middle base plate adapted to project under the traffic rail, clamp means on said plate adapted to engage the traffic rail, a vertical integral web rising from the end of said plate opposite the clamp means and comprising faces adapted to form a guard rail and a foot guard, said guard rail and foot guard being curved down at their outer ends, and end base plates integral with said ends of the guard rail and foot guard, substantially as described.

7. In combination, a traffic rail, a tie, a curved guard rail disposed with its convex face toward the traffic rail and adapted at its center only to engage the base of the latter, a central base plate integral with the guard rail and adapted to project under the traffic rail and between it and a tie, adjustable wedge means mounted on said base plate and adapted to clamp the traffic rail against the guard rail, means to secure the wedge means in adjusted position, and means to brace the guard rail.

8. In combination, cross ties, a traffic rail, an integral guard rail structure comprising a foot guard web, a guard rail rising above the web and curved with its convex face toward the traffic rail, an arched supporting web for said foot guard and guard rail which is curved vertically and horizontally, an intermediate and end base plates integral with the ends of the arches of said arched web and spaced to rest on the ties and project under the traffic rail, and clamp means on the intermediate of said base plates to fasten the traffic rail and guard rail together, substantially as described.

9. In combination with a guard rail and traffic rail, a base plate connected to the guard rail and projecting under the traffic rail, a cross tie supporting said plate, an undercut shoulder on said base plate beyond the traffic rail, and a wedge key adapted to be driven under said shoulder and between it and the traffic rail, said key having a lug adapted to engage over the base of the traffic rail.

10. In combination with a guard rail and traffic rail, a base plate connected to the guard rail and projecting under the traffic rail,

fic rail, a cross tie supporting said plate, an undercut shoulder on said base plate beyond the traffic rail, and a wedge key adapted to be driven under said shoulder and 5 between it and the traffic rail, said key having lugs adapted to engage over and under the base of the traffic rail.

11. In combination with a guard rail and traffic rail, a base plate connected to the 10 guard rail and projecting under the traffic rail, an undercut shoulder on said base plate beyond the traffic rail, and a wedge key adapted to be driven under said shoulder and between it and the traffic rail, said key 15 having lugs adapted to engage over and under the base of the traffic rail, the overhanging lug standing over the base plate while the underhanging lug stands clear of the base plate.

12. In combination with a guard rail and traffic rail, a base plate connected to the guard rail and projecting under the traffic rail, a cross tie supporting said plate, an undercut shoulder on said base plate 20 beyond the traffic rail, a wedge key adapted to be driven under said shoulder and between it and the traffic rail, said key having lugs adapted to engage over and under the base of the traffic rail, the overhanging lug 25 standing over the base plate and tie while the underhanging lug stands clear of the base plate and tie, there being a slot in the base plate and a notch in the key opposite the overhanging lug, and a spike adapted 30 to be driven through the notch and slot to secure the traffic rail, wedge key and base plate to the tie.

13. In combination with a guard rail, a base plate connected thereto and adapted to 35 project under the traffic rail, spaced undercut shoulders on the base plate, a wedge key adapted to be interposed between said shoulders and the base of the traffic rail, there being a slot in said base plate between said shoulders, and there being a spike notch on the wedge adapted to travel in register with said slot, said wedge key being provided with an intermediate raised lug adapted to overhang the traffic rail base 45

and having near its large end a depressed lug adapted to engage under the base of 50 the traffic rail, substantially as described.

14. In combination with a guard rail, a base plate connected thereto, a traffic rail, a cross tie, the base plate being adapted to 55 be interposed between the tie and traffic rail and adapted to project beyond the latter, spaced undercut shoulders on said base with their inner walls disposed in a plane inclined to the traffic rail, there being an inclined slot in the base plate between said shoulders, and a wedge key adapted to fit under said shoulders and between them and the traffic rail, said key being substantially longer than the width of the cross tie and 60 having near its larger end a lug adapted to engage under the traffic rail and having at an intermediate point a raised lug adapted to overlie the base of the traffic rail, there being a spike notch in the key adapted to 65 travel over said slot in the base plate.

15. The combination with a traffic rail, a tie, a guard rail and a base plate, of wedge means to clamp the guard rail to the traffic rail comprising a wedge key adapted to engage the traffic rail base and having a lug adapted to engage the top of said rail base above the cross tie, and a lug adapted to engage the bottom of the rail base clear 75 of the tie, and an overhanging abutment 80 for the wedge key on said base plate.

16. The combination with a traffic rail, a tie, a guard rail and a base plate, of wedge means to clamp the guard rail to the traffic rail comprising a wedge key adapted to 85 engage the traffic rail base and having a lug adapted to engage the top of said rail base above the cross tie and a lug adapted to engage the bottom of the rail base clear of the tie, an overhanging abutment for 90 the wedge key on said base plate, and means to spike the key in its adjusted position to the cross tie.

In testimony whereof I affix my signature.

ROBERT S. BOHANNAN.
